UNITED STATES PATENT OFFICE

HERBERT WILLIAM HUNT AND PERCY HUNT, OF MANCHESTER, ENGLAND

MACHINE FOR SHARPENING SCREWING TAPS AND THE LIKE

Application filed August 3, 1931, Serial No. 554,766; and in Great Britain August 19, 1930.

This invention refers to a new or improved construction of machine for sharpening or resharpening screwing taps and the like.

- 5 Screwing taps are made with a tapered or bevelled end, and such tapering or bevelling is given a "backing off." Resharpening of screwing taps is commonly effected by grinding back the teeth at the flutes. The principal wear on a tap however occurs at the leading or bevelled end, so that the taps can also be sharpened by taking the bevelling further back which, while shortening the tap, does not thin or weaken the teeth.
- 10 15 The object of the invention is to enable the bevelling to be applied to taps efficiently and uniformly.

According to the invention, the improved tap sharpening or resharpening machine 20 comprises means for holding and rotating the tap and means for simultaneously advancing and withdrawing the tap laterally with respect to a grinding wheel for each cutting edge.

25 In the accompanying drawings:—

Fig. 1 is a front elevation of the upper part of one example of tap grinding machine made in accordance with the invention.

Fig. 2 is a plan of Fig. 1.

30 Fig. 3 is an end elevation.

Fig. 4 is a front elevation of the headstock and tailstock unit.

Fig. 5 is an end elevation of Fig. 4.

35 Fig. 6 is a sectional elevation on line 6—6 of Fig. 4.

Fig. 7 is a detail view of the stop plate.

As illustrated, the machine comprises a pedestal 10, the upper part only of which is shown, on which is mounted the usual tray 11 and the grinding wheel 12. The spindle of the grinding wheel 12 is mounted in a bracket 13, and is provided with fast and loose pulleys 14 and 15. Formed as part of the tray are brackets 16 for a slide bar 17, and at the front edge of the tray a machined sliding face 18 below which is formed a groove 19. The main carriage 20 rests on the slide bar 17 and the sliding face 18 and is held to the bar 17 by half bearings secured 45 by bolts 21 and to the sliding face by a re-

taining piece 22 having a projection engaging the groove 19 and secured to the slide by bolts 23. The tray 11 has lugs 24 carrying a slide screw 25 having an operating wheel 26. The main slide 20 is formed with 55 a depending lug 27 screwed to fit on the slide screw 25. On the upper face of the main slide 20 is a supporting lug 28 and upstanding slide lugs 29 and 30 which latter are undercut to receive a slide 31. The front 60 lug 29 is screwed for a slide screw 32 provided with an operating wheel 33, the screw being joined in a lug 34 at the front end of the slide. Projecting from one side of the slide is a web 35 on the upper face of which 65 is formed a quadrant 36 which will be graduated in degrees of angularity. The under side of the web is formed with a machined face to engage with the face of the supporting lug 28. On the other side of the slide 70 31 is a lug 37 for a vertical pivot which forms the centre of the quadrant. Supported on the upper face of the quadrant 36 and lug 37 is an undercut slide rail 38 secured by bolts having clamping nuts 39 75 and 40, the nut 39 holding a retaining plate 41. On the slide rail 38 are brackets 42 and 43 which carry an overhanging shaft 44 on which are keyed the headstock 45 and tailstock 46. The brackets 42 and 43 are adjustably secured on the slide rail 38 by wing nuts 42^a and 43^a. On the bracket 42 is formed an upstanding lug 47 on the side of which is mounted an abutment roller 48 and in which lug 47 is housed a spring 49 for 80 the tie bolt 50 connected to the headstock. In the headstock is mounted the chuck spindle, on one end of which is mounted the chuck 51. In the bearing of the headstock is a friction pad 52 engaging the 85 chuck spindle and having a spring 53 and adjustable nut 54 to regulate the pressure. On the chuck spindle behind the headstock bearing is a lever handle 55, rotatable on the spindle. On the side of the lever handle against the headstock bearing is supported a cam plate 56 located on a stud 57 and an eccentric 58 in the face of the lever, (see Fig. 6). The eccentric 58 is provided with a pointer 59 co-operating with a scale 100

60 on the lever arm 55, the eccentric being secured in any desired position by a locking screw 61 in the lever arm. The cam plate 56 engages the abutment roller 48. Behind the lever arm 55 are ratchet wheels 62 and 63 having respectively 63 and 120 teeth, the wheels being keyed to the chuck spindle. On the lever arm 55 are pawls 64 and 65, marked A and B respectively to engage the ratchet wheels. On the end of the chuck spindle is a stop plate 66 having a stop lug 67 projecting across the front of the ratchet wheels to be engaged by the pawls 64 or 65. The stop plate is graduated 10 and held in any desired position by a clamp 68 fastened by a clamping nut 69 to the end of the shaft 44. The lever 55 has a stop 70 engaging a projection 71 on the foot 72 of the headstock by which the headstock is 20 mounted on the shaft 44.

For grinding the flutes of the taps an attachment is provided in a bracket 73 secured to the back of the grinding wheel bracket 13, and consisting of an arm 74 carrying a grinding wheel 75 and embodying suitable shafts and bevel wheel drive, fast and loose driving pulleys 76 and 77 being provided. The arm 74 can be brought down to engage the tap, being 30 pivoted about the driving shaft in the bracket 73 and is provided with an adjustable stop screw 78 adapted to position the height of the wheel over the tap by engaging a lug 79.

35 Instead of belt drive, electric motors may be coupled direct to the grinding wheels.

In operation, the machine is operated by the simple action of giving the lever arm a to-and-fro movement between its stops.

40 The stop plate 66 is set according to the number of flutes on the tap so that the movement of the lever arm gives the tap a part rotation being $\frac{1}{3}$ of a turn for a three flute tap, and so on. The plate is graduated 45 with the number and letters as follows:—

B A A A B A B A A
3 4 5 6 7 8 9 10 12

The letters A and B indicate the pawl to be used for the setting chosen and as will be 50 seen bring into use the ratchet wheel having the number of teeth which is a multiple of the number of flutes.

The tap is presented to the grinding wheel by means of the operating wheels 55 33 and 26 and is set in the chuck in the first instance by a vertical straight-edge placed across a flute, which setting allows the grinding of each set of teeth to be carried to the extreme back edge without 60 catching the front or cutting edge of the next set of teeth against the grinding wheel.

The setting of the cam for the backing off is obtained by means of the eccentric, the position of which is indicated by the pointer 65 59, the rotation of the eccentric causing

the cam plate 56 to be raised or lowered, the lateral movement being substantially negligible and of no effect.

The headstock and tailstock rock on the shaft 44 with each movement of the operating lever 55 by reason of the cam 56 engaging the abutment roller 48, the spring 49 holding the headstock cam against the roller. The tap is thus given an advancing or withdrawal movement simultaneously with each part rotation as the handle is pulled down and is again withdrawn or advanced without rotation as the operating lever is returned, the friction pad 52 holding the chuck 75 spindle from rotation.

80 The above combined movement gives the required "backing off" and equally to each set of teeth.

85 The taper to be given to the tap is determined by the angular setting as indicated at the quadrant 36.

For grinding the flutes, the angular setting is returned to zero and the wheel 33 operated to bring the tap away from the grinding wheel 12 and into position for the wheel 75. All the flutes may be ground to the same depth and the cutting edges to the correct 90 part rotation of the tap.

95 In the matter of constructional details, variations may be made in the machine without departing from the invention, the essential features of which are (1) the movement of the tap rotationally and bodily while in contact with the grinding wheel, and (2) the provision of means for varying the rotational movements to suit the make of tap 100 to be sharpened.

105 What we claim is:—

1. In a grinding machine for sharpening 110 screwing taps and the like having a headstock and tailstock mounted to rock about an axis parallel to the axis of the tap and having a cam on the headstock engaging a fixed abutment to produce such rocking motion synchronously with the rotation of the headstock, in combination, a lever rotatably mounted on the axis of the headstock, and carrying the cam, a ratchet wheel secured on the spindle of the headstock adjacent to the lever, a pawl on the lever to engage the ratchet wheel, means for preventing the reverse rotation of the headstock and adjustable means for limiting the arc of movement of the lever.

115 2. In a grinding machine for sharpening 120 screwing taps according to claim 1, two ratchet wheels adjacent to the lever having a different number of teeth, a pawl for each wheel on the lever and means for holding either pawl out of engagement with its wheel.

125 3. In a grinding machine for sharpening 130 screwing taps as claimed in claim 1, the means for limiting the arc of movement of the lever consisting of a calibrated quadrant.

shaped plate on the axis of the headstock with a stop projection lying in the path of the pawl, and a clamp on the base of the headstock to hold the plate in a set position.

5 4. In a grinding machine for sharpening screwing taps and the like according to claim 1, a main grinding wheel supported in fixed bearings, an auxiliary flute-grinding wheel rotating at right angles to the main grinding wheel and supported in pivotally mounted bearings so as to be moved into and out of grinding position, guides parallel with the axis of the main grinding wheel, a slide mounted on the guides and a headstock carrier pivotally mounted on the slide so as to be adjustable to bring the tap into the plane of each wheel and at a different angle to each plane.

10 20 In testimony whereof we have signed our names to this specification.

HERBERT WILLIAM HUNT.
PERCY HUNT.
